ELECTRICAL CONNECTOR

Horatio H. Burtt, Hartsdale, William W. Koenig, Flushing, and Leon Gilbert, New York, N. Y., assignors to Winchester Electronics, Inc., New York, N. Y.

Application December 9, 1949, Serial No. 6,523

Term of patent 7 years

(Cl. D26—13)

To all whom it may concern:

Be it known that we, Horatio H. Burtt, William W. Koenig and Leon Gilbert, respectively, a citizen of the United States, a resident of 50 Cater-
son Terrace, Hartsdale, New York; a citizen of the United States, a resident of 141-07 73rd Avenue, Flushing, Long Island, New York; and a citizen of the United States, a resident of 68 West 10th Street, New York, New York, have invented a new, original, and ornamental Design for Electrical Connectors, of which the following is a specification, reference being had to the accompanying drawing, constituting a part hereof.

Fig. 1 is a perspective view of an electrical connector, showing our new design.

Fig. 2 is a side elevational view,

Fig. 3 is a bottom plan view,

Fig. 4 is an end view,

Fig. 5 is a fragmentary perspective view with the pivoted member in raised position, and

Fig. 6 is a collective view of the parts separated from one another.

The dominant features of my design reside in that portion shown in full lines in the drawing.

We claim:

The ornamental design for electrical connectors, substantially as shown and described.

HORATIO H. BURTT.
WILLIAM W. KOENIG.
LEON GILBERT.
